UNITED STATES PATENT OFFICE.

JOHN WALDHEIM, OF NEWARK, NEW JERSEY.

RAZOR-STROPPING DEVICE.

1,284,829.

Specification of Letters Patent. Patented Nov. 12, 1918.

Application filed November 13, 1911. Serial No. 659,901.

To all whom it may concern:

Be it known that I, JOHN WALDHEIM, citizen of the United States, and resident of Newark, in the county of Essex and State 5 of New Jersey, have invented certain new and useful Improvements in Razor-Stropping Devices, of which the following is a specification.

My invention relates to razor stropping devices in which the razor strop is carried by the strop. Among the objects of my invention are, first; to provide a strop with a plurality of stropping surfaces, any one of which can be brought into co-operation with the razor strop when desired; second, to provide a blade holder capable of taking razor blades of several different shapes, said blade holder being detachable from the stropping device; third, to provide simplified and effective means for oscillating the blade holder; fourth, to provide means for preventing the strop from displacement on its support; fifth, to provide new and improved means to cause the razor 20 blade to move back and forth across the strop while it is being pulled along on the strop; and sixth, to provide improved means for reversing the blade automatically, and for pressing it properly against the strop. 25 My invention also has the object of improving devices of the class specified, in other particulars as will appear hereinafter.

To the above ends, my invention consists in certain features of construction and combinations and arrangements of parts which will be fully set forth herein and particularly pointed out in the claims.

I attain the objects above specified by the mechanism illustrated in the accompanying drawings, in which—

Figure 1 is a vertical section of the device taken on the line $x-x$ of Fig. 2 and looking in the direction of the arrow at said line and shows the parts in the positions they 45 occupy when the device is traveling in the direction of the arrow at the handle.

Fig. 2 is a plan view of the device.

Fig. 3, in which some of the parts are shown broken away, shows the parts as seen 50 when looking at the left side of the device, the parts shown having the same positions as in Fig. 1.

Fig. 4 is a sectional view of the blade holder on its support and holding one form 55 of razor blade.

Fig. 5 is a sectional, detached view of the

blade holder with one of the blade holder members swung about its pivot to receive the razor blade.

Fig. 6 is a section taken on the line $y-y$ 60 of Fig. 4 and looking in the direction of the arrow at said line.

Figs. 7 and 8 are views similar to Fig. 4, but showing different forms of blades in the holder.

Fig. 9 shows a part of the strop and the wavy path in which the edges of the razor 65 blade travel.

Fig. 10 is a detail perspective view of the rock shaft upon which the blade holder is 70 supported.

Fig. 11 is a detail perspective view of the friction wheel and its slotted hub.

Fig. 12 is a detail perspective view of the 75 sliding frame or carriage with some of the working parts omitted.

Fig. 13 is a detail perspective view of the sleeve to which the blade holder is attached.

Fig. 14 is a detail perspective view of the shifting frame and the operating handle.

Fig. 15 is a diagrammatic view and illustrates the advantage of the bend in the strop.

Figs. 16 and 17 are detail views of the two 85 parts of the blade holder.

Fig. 18 is a perspective view of the holding or clamping device for the strop.

Figs. 19 and 20 are plan and side views respectively of a modified form of strop which can be used with my stropping device.

Fig. 21 is a vertical section of the carriage taken on the line $z-z$ of Fig. 1 and looking in the direction of the arrow, the shifting frame being omitted.

Like numerals refer to like parts throughout the several views of the drawing.

In the drawing is shown a sliding frame or carriage comprising side plates 1 which are connected by cross rods 2 which carry rollers 3 and 4, the cross rods 2 and rollers 3 and 4 serving as turning bars for guiding a strop 5. The sliding frame or carriage is supported by and movable on the strop 5. Said strop is preferably continuous or endless in the form of a belt and is carried by 105 two semi-cylindrical supports 6 and 7 which serve also as separators for the sides or layers of the strop.

In the side plates 1 of the sliding frame or carriage is journaled a rock shaft 8 upon 110 which is mounted a blade holder which will be hereinafter described. Said rock shaft

2
has at one end a crank arm 9 having thereon a slot 10. The side plates 1 also have ears 11 which project downwardly and on which is mounted blade-shifting means consisting

5 of a shifting frame pivoted to said ears, this frame comprising arms 12 secured to a cross rod 13. The arms 12 have holes 14 (Fig. 14,) through which shouldered screws or pivots 15 are passed and threaded into the ears 11.

10 To the shifting frame, on the rod 13, is pivoted a handle frame comprising a cross piece 16 with bent up ears 17 and a handle 18.

In order to transmit motion to the rock shaft 8, one of the arms 12 has an upwardly 15 extending bent off portion 19 which has at its upper end a pin 20 which co-operates with the slot 10 of the crank arm 9 extending from the rock shaft.

From the foregoing description it is obvious 20 that when the handle 18 is moved in the opposite direction of the arrow (Fig. 1) it will cause the shifting frame to rotate on its pivots 15, thus transmitting motion to the crank arm 9 and causing the rock shaft to rotate, carrying with it the razor blade, the path of the edge of the blade being indicated by the arc *a* in Fig. 1.

It will be understood that the first part of 30 the motion of the handle will oscillate the blade, thus directing the blade in the opposite direction to that of the travel of the handle and a further motion of the handle will cause the shifting frame or carriage to move along the strop, causing the razor to slide on the

35 strop.

It will also be understood that the rotative motion of the shifting frame is stopped by the razor blade striking the strop 5, and that while the carriage, or main frame, is being pulled along the strop by the handle and the shifting or secondary frame, the tendency of the handle is to rotate the shifting frame, thus causing a pressure on the edge of the blade against the strop 5.

40 The tendency of the operator is to take a firm grip on the handle and hold the handle substantially parallel, while moving the carriage along on the strop to the position it has when the carriage starts to move, the starting position of the handle 18 being any one intermediate or beyond the two dotted line positions shown in Fig. 1.

In order to accomplish the foregoing, I have formed a pivotal connection between 55 the shifting frame and the handle frame so as to allow an independent rotative motion of the handle frame relatively to the shifting frame. The blade is thus reversed and pressed properly against the strop in whatever position the operator holds the handle. With this construction it is impossible for the operator to control the razor blade, from the operating handle, to accidentally cut into the strop.

60 Another advantage of pivoting the handle

frame to the shifting frame is to allow the handle 18 to lie close to the strop while storing the device.

The blade holder shown in the accompanying drawing is capable of receiving 70 razor blades of several different shapes. In the present instance I have shown three styles of blades B, C, D, (Figs. 4, 7 and 8, respectively). The blade holder consists of two members or elements 21, 22 pivotally 75 connected. The member 21 has two spring fingers 23 which project laterally under bent-up portions 24 of the member 22, thus forming the pivotal connection between the members 21 and 22. The members 21 and 22 80 have rearwardly extending fingers or jaws 25 which embrace a sleeve 26 mounted on the rock shaft 8. Each finger 25 has at its end a bent retaining portion 27 adapted to snap over the sleeve 26 and terminates in a 85 cam portion 28. One of the elements 21, 22 has two arms 25 at its ends and the other of said elements has one arm 25 in its middle, so that, when removed from the sleeve 26, 90 said elements are capable of opening up wide as shown in Fig. 5.

For the purpose of positioning the razor blades in the holder, I have provided the member 22 with two spring fingers 30, (Fig. 17), which are integral with the member 95 22, and have at their ends bent off at 31 rounded flat portions 32. To position any of the razor blades the member 21 is swung about its pivot 23, 24 to a position shown in Fig. 5, although it may be swung farther 100 if desired. The blade B is shown as a Gillette blade, which has two holes 33 through it. If this blade B is to be attached, it is placed on the member 22 so that the rounded portions 32 will fit into said holes 33. If it 105 is desired to attach the razor blade C which is provided at one end with a piece of bent metal 34, it is placed on the member 22 and pulled forward until the metal piece 34 strikes the rounded portions 32 of the blade 110 holder, thereby positioning the blade C on the holder. D is a Star blade which has the cross section of an ordinary razor, and the members 21, 22, except the arms 30 are made to conform to this shape, as shown in Figs. 115 8 and 15. This blade, when it is inserted, is first laid on the member 21 which conforms to its shape. After positioning any one of these razor blades B, C or D, the blade holder is then closed by swinging the 120 two members 21 and 22 toward each other.

By an inspection of Figs. 4, 7 and 8 it will be seen that when the blade B is attached (Fig. 4) it is held in position by the rounded portions 32 and clamped by the 125 members 21 and 22 at 35 and 36. When the blade C is attached (Fig. 7) it is positioned by the rounded portions 32 and clamped by the members 21 and 22 at 35 and 37. When the blade D is attached it is held 130

in position by the members 21 and 22 as they both conform to the shape of the blade and is clamped thereby, the rounded portions 32 which position the blades B and C being forced back out of the space occupied by the blade holder.

To attach the blade holder to the rock shaft I have provided the sleeve 26 which is splined to the rock shaft 8 by a rib 39 on the rock shaft 8 and a groove 40 in the sleeve 26. The purpose of mounting the sleeve 26 in this manner will hereinafter be more fully explained. The sleeve 26 is also provided with three cut outs or flattened parts 41. When attaching the blade holder the sleeve is first turned to a convenient position and the cam faces 28 of the fingers or jaws 25 are set against the edges 42 (Fig. 13) of the cut outs 41. When a push is exerted at right angles to the member 26 the bent portions 27 of the fingers 25 will ride up on and over the flat surfaces of the cut-outs 41, the member 26 acting as a wedge thus causing the members 21 and 22 to separate slightly at the rear against the tension of the spring fingers 23 of the member 21 and producing a clamping effect, of the members 21 and 22, on the razor blade. It is obvious that the blade holder is clamped on the sleeve by the fingers 25 bearing on the flat surfaces of the cut-outs 41 and is held thereon by the bent off portions 27. It will be understood that when the blade holder is on the sleeve the spring fingers 23 of the member 21 are under tension.

Referring again to the oscillating of the blade holder and then moving it along the strop, I have provided means for causing a resistance of the sliding frame or carriage on the strop, said resistance being variable on the strop, said resistance being variable according to the pull exerted on the strop, thus producing a variable pressure of the razor blade on the strop which is controlled by the latter. This I have accomplished by guiding the strop 5 through a series of staggered rollers or turning bars. The resistance of the carriage is always such that when the handle 8 is moved the carriage will be held back until the razor blade is received and comes in contact with the strop when all the parts will be moved along on the strop. With this construction it is impossible to accidentally cut into the strop, the razor blade being reversed before it is moved bodily lengthwise of the strop. Ordinarily, the rock shaft 8 will turn to the position shown in Fig. 3. By an inspection of this figure it will be seen that the rock shaft is capable of being rotated still farther as the pin 20 has not yet reached the end of the slot 10. By increasing the pull on the strop 5 through the handle 44 the resistance of the carriage can be increased so as to cause the pin 20 to travel

to the end of the slot before the carriage is set into motion, the crank pin 20 and the end of the slot 10 acting as a pair of co-operative stops for limiting the motion of the shifting frame. During the time that the pin is traveling from the position shown in Fig. 3 to the end of the slot the sleeve is caused to rotate slightly between the fingers or jaws 25 of the blade holder, thus flexing the spring fingers 23 and causing a greater pressure of the razor edge on the strop. This does not take place unless it is desired to increase the pressure of the blade against the strop.

By a further inspection of Fig. 3 it will be understood that when the shifting frame is set into motion its effect on the blade holder will be to give it a very slow start and its motion will be accelerated until it reaches a vertical position from where its motion will be retarded thus causing the blade to meet the strop gently and not strike it a glancing blow. Another feature is obvious in this figure which is, that the weight of the handle 18, when said handle is let go and allowed to hang freely, will position the parts so as to normally hold the razor blade away from the strop.

I provide the rollers 3 to guide the strop and insure that the strop takes the same path between the rollers 3 and 4 at all times so as to maintain the proper stropping angle between the razor blade and the strop.

Another advantage of guiding the strop through a series of rollers and having it take the course as shown in the drawing, besides that of causing resistance on the strop, is illustrated in Fig. 15 which shows, by the dotted line b, the plane in which the strop would lie if it were allowed to take a straight course. By causing a bend in the strop to one side of and in the vicinity of the rock shaft 8, I arrange the parts so as to obtain the true stropping angle between the stropping surface and the razor blade. This is illustrated in the figure referred to where the corner 45 of the razor blade D and the cutting edge are in the same plane as that part of the strop between the rollers 3 and 4. This feature could not be attained if the strop were allowed to take a straight course, as the thickness of the metal of the blade holder at 46 would prevent the corner 45 of the razor blade from coming in contact with the strop.

Still another advantage of bending the strop in the vicinity of the rock shaft is to make clearance for parts mounted on the rock shaft.

While the razor blade is drawn longitudinally along the strop I also desire to have it travel across the strop from side to side so as to give it a waving motion relatively to the strop as indicated in Fig. 9, by dotted lines c. To accomplish this, I have

mounted on the rock-shaft 8 a friction wheel or cam member 47 which is loose on the shaft and provided with a peripheral cam groove 48. The sleeve 26 has an arm 49 projecting laterally and the arm 49 has a rounded portion 50 bent off from it to engage in the cam groove 48. A roller 43 is provided beneath the rock shaft 8 with reduced ends 51 and 52 which are allowed to play in slots 53, 54 respectively (Fig. 21).

It is obvious that when the carriage is moved along on the strop, the strop will first cause the roller 43 to rise until it is stopped at one end by bearing against the wheel 47 and the end 52 bearing in the upper end of the slot 54 the roller 43 will be caused to roll on the strop and transmit motion to the wheel 47, thus causing the sleeve 8 and the blade holder to move back and forth diagonally across the strop.

By having a bend in the strop as described and allowing the reduced ends of the roller 43 to play in elongated slots 53 and 54 it will be understood that the pressure of the roller 43, influenced by the strop 5, against the friction wheel or cam member 47 can be increased by increasing the pull on the strop.

As I have stated before, the strop 5 is preferably continuous or endless, and is carried by semi-cylindrical supports 6 and 7. The reason for making the strop continuous or endless is to provide it with two stropping surfaces *e* and *f* which can be conveniently shifted so as to bring any of the desired surfaces into coöperation with the razor strop and to do this without detaching the stropping device from the strop. To shift the strop it is simply pulled along one side and caused to slide around over its semi-cylindrical supports. One of the halves *e* and *f* of the strop, is coarse and the other is finer for finishing purposes.

In order to prevent the fingers of the operator from coming in contact with the lower half of the strop while the razor strop is being moved along on the strop by the aid of the handle 18, I provide guards 55 at the top of said handle.

The semi-cylindrical support 6 has bent off from its sides ears 56 which carry a cross pin or rod 57 upon which is mounted the handle 44. The handle 44 consists of a piece of leather or other suitable material bent over, glued and sewed as at 58 with an opening 59. The cross pin 57, which is reduced at its ends, is slipped through the opening 59 and ears 56 sprung apart to allow the reduced ends of the pin 57 to enter the holes in said ears 56 of the semi-cylindrical support 6. In this way the handle and support are assembled.

To prevent the strop 5 from slipping on its supports 6 and 7, I have provided clamping means, said means being carried by the support 7 which will now be described.

The support 7 has bent off from its sides ears 60 similar to the ears 56. Two curved plates 61 which in part conform to the curvature of the strop around the support 7, are provided with ears 62 and 63 bent off from their sides and pivoted to the ears 60 at 64. Each plate 61 is also provided with fingers 65 bent off from it, said fingers being provided with cam faces 66. The fingers 65 grip over a link 67, said link providing means for fastening the device to some stationary object, here shown as hook 68.

From the foregoing description it will be understood that when a pull is exerted on the handle 44 or on the upper and lower part of the strop 5, the fingers 65 tend to wedge apart, thus causing the plates 61 to swing about their pivots 64 and press against the strop 5, thus clamping said strop against the support 7.

It will be understood that when the pull on the handle 44 is relieved, the clamping effect of the clamping means is also relieved and when a pull on one side of the strop is effected, this will not affect the clamping device and will not interfere with the shifting of the strop. To get the locking effect of the strop a pull must be exerted on the upper and lower half of the strop at the same time and in the same direction and this is done by pulling on the handle 44.

The reason I employ the locking device above described is to insure that the strop does not shift while the razor strop is being drawn along on the upper half of the strop. As it may not be necessary to use this clamping device in all instances, for instance, when the surfaces of the strop are rough, I think it advisable to use it where the surfaces are very smooth.

In Figs. 19 and 20 I have shown a modified form of strop 68 which may be used with my razor strop which, like the strop 5, has two surfaces *g* and *h* of different stropping characters, the stropping machine being shiftable from one surface to the other by moving it lengthwise of the strop, the difference in the two strops being that the latter is not in the form of an endless belt, but is straight and is supported at its ends. It should be understood that the strop can be shifted from one surface to another, of the continuous strop, as in the modification. To accomplish this the strop must first be shifted on its support to bring the ends of the two surfaces midway between the two supports 6 and 7.

To use this device the razor is first stropped on one surface and then shifted over to the other surface, and stropped, without taking the razor-strop off the strop. It is obvious that this form of strop can also be used with other forms of razor stroppers.

It will be apparent that some of the

features of my invention can be applied to other forms of devices than the specific one shown in the drawing and parts of it can be used without others.

5. What I claim as new and desire to secure by Letters Patent, is:—

1. A razor-stropping device comprising the combination of a frame, a blade-holder mounted therein, blade-shifting means mounted on the frame and connected with the blade-holder, and a handle pivoted to and supported by the blade-shifting means, the frame including parts which fit on a strop and being movable to and from supported by the strop.

2. A razor-stropping device comprising the combination of a frame, a blade-holder mounted therein, blade-shifting means, and a handle, the blade-shifting means including an arm pivoted to the frame and connected with the blade-holder, the handle being pivoted to and supported by the blade-shifting means, and the frame including parts which fit on a strop and being movable to and from supported by the strop.

3. A razor-stropping device comprising the combination of a main frame, a rock-shaft mounted therein, a blade-holder on the rock-shaft, a secondary frame pivoted to the main frame and connected with the rock-shaft, and a handle pivoted to the secondary frame on an axis transverse to the length of the handle, the main frame including parts which fit on a strop and being movable to and from supported by the strop.

4. In a razor-stropping device the combination of a strop, a frame on said strop, a blade-holder pivoted on said frame, means for guiding the strop to clear the blade-holder, and means to one side of the blade-holder for guiding the strop so that the extended plane of said strop, at said guiding means, cuts the blade-holder when the latter has a position nearest the strop.

45. 5. In a razor-stropping device the combination with a frame and a rock-shaft mounted therein, of a sleeve splined on the rock-shaft, and means for axially reciprocating the sleeve on the shaft, the sleeve and rock-shaft forming a support for a blade-holder.

6. In a razor-stropping device the combination of a strop, a frame on the strop, a rock-shaft mounted in the frame, a sleeve splined on the rock-shaft, a blade-holder on the sleeve, an arm extending from said sleeve and having on it a pin, a friction-wheel on the rock-shaft, the friction-wheel having a hub containing a cam-slot into which said pin extends, and means operated by the strop to rotate the friction-wheel.

7. A razor-stropping device comprising the combination with a frame that fits on a strop and has sides between which the strop extends, and a blade-holder support pivoted at its ends to the sides of the frame, of a blade-holder having pivotally connected jaws between which said support extends, the support having flat surfaces on which said jaws fit, and shoulders which extend outward from said surfaces close to the jaws.

8. A razor-stropping device comprising the combination with a frame that fits on a strop and has sides between which the strop extends, and a blade-holder support pivoted at its ends to the sides of the frame, of a blade-holder having clamping jaws that are pivotally connected together by means constituting a spring, the support having outwardly facing surfaces on which said jaws fit on opposite sides of the support, and the spring being under stress when the blade-holder is attached to the support.

9. A blade-holder comprising two parts forming a pair of support-clamping jaws and a pair of blade-clamping jaws and a resilient pivotal connection by which said parts are secured together between the pairs of jaws and on which the clamping action of both pairs of jaws depends.

10. A blade-holder comprising a pair of support-clamping jaws and a pair of blade-clamping jaws and means by which they are secured together and on which the clamping action of both pairs of jaws depends, said means including a resilient pivotal connection, and said pairs of jaws being on opposite sides of that connection.

11. A blade-holder comprising a support-clamping jaw and a blade-clamping jaw formed of one piece of material, and another support-clamping jaw and another blade-clamping jaw formed of another piece of material, and a resilient pivotal connection by which said two pieces of material are secured together and on which the clamping action of the support-clamping jaws and blade-clamping jaws depends.

12. In a razor-stropping device, a blade-holder comprising two clamping elements, and a resilient connection between said elements, said resilient connection comprising spring fingers carried by one of said elements which coact with bent up portions of the other element.

Signed at the borough of Manhattan, city, county and State of New York, this 11th day of November, 1911.

JOHN WALDHEIM.
